UNITED STATES PATENT OFFICE.

FRANK A. HAUGH, OF WINFIELD, KANSAS.

UNDERREAMER.

1,328,955.

Specification of Letters Patent. Patented Jan. 27, 1920.

Application filed March 10, 1919. Serial No. 281,602.

To all whom it may concern:

Be it known that I, FRANK A. HAUGH, a citizen of the United States, residing at Winfield, in the county of Cowley and State 5 of Kansas, have invented certain new and useful Improvements in Underreamers, of which the following is a specification, reference being had to the accompanying drawings.

10 This invention relates to well drilling tools, and particularly to underreamers.

Underreamers are used in order to enlarge the bore of a well beneath the well casing, and the main object of this invention is the provision of a very simply constructed underreamer which will automatically expand when it has been lowered into the well and past the lower end of the well casing, and which will be automatically contracted when it is raised and drawn upward through the well casing.

25 And a further object is to provide an underreamer so constructed that sufficient cutting surface will be provided as to avoid any danger of leaving lumps or rough places on the wall of the bore which might impede or absolutely prevent the lowering of the well casing in deep wells.

30 A further object is to provide a reamer of the character described of particularly strong construction so as to stand the work to which it is subjected.

35 A further object is to provide cutters which, when expanded, have portions disposed upon the exterior of the body of the reamer and which, when expanded, are inserted within a downwardly projecting lip or flange of the body of the reamer so that the upper portion of the cutter is 40 strengthened and supported both upon the inner and the outer part of the cutter.

45 A further object is to provide a reamer of this character which may be readily set so as to enter the well casing and will ride easily through the well casing, both when it is being lowered and when it is being raised.

50 Other objects will appear in the course of the following description.

55 My invention is illustrated in the accompanying drawings, wherein:—

Figure 1 is a vertical longitudinal sectional view of a reamer constructed in accordance with my invention:

Fig. 2 is a bottom plan view of the construction as in Fig. 1;

Fig. 3 is a fragmentary vertical section showing the bits contracted and the reamer ready to be inserted in a well casing;

Fig. 4 is a section on the line 4—4 of Fig. 1;

Fig. 5 is a perspective view of one of the bits; and

Fig. 6 is a perspective view of the hanger rod and the hanger block. 65

Referring to these drawings, it will be seen that the body 10 of the reamer is solid at its upper end and formed to be engaged by the drill supporting rods or other like devices. The lower portion of the body 70 is cylindrical for its entire extent, but adjacent the lower end of the body 10, the body is preferably diametrically enlarged, as at 11, and this enlargement at its lower edge is upwardly and inwardly beveled, as 75 at 12, so as to leave a downwardly extending lip. The upper end of the enlargement 11 is beveled upwardly and centrally, as at 13. Below the overhanging lip or inclined lower face 12 of the portion 11, the 80 body 10 is downwardly and centrally tapered slightly, as at 14.

The body 10 is hollow for the greater portion of its length, and to this end the body 10 is formed with a relatively large 85 bore 15 extending from the lower end of the body for a certain distance. Above this, the bore is contracted, as at 16, for a distance and then again the bore is contracted, as at 17, for a distance. A slightly beveled 90 shoulder 18 is formed at the junction of the bores 15 and 16, and a shoulder 19 is formed at the junction of the portions 16 and 17. Intersecting the relatively small counter-bore 17 is a passage 20 which is disposed 95 tangential to a circle concentric to the bore and adapted to receive a pin 21. Also intersecting the bore 17, but not passing entirely through the body, is a longitudinally disposed slot 22. 100

Disposed within the hollow interior of the body is a cutter supporting rod or hanger 23, and disposed within the bore 17 is a head 24 through which the rod 23 slides, this head being held in place from downward movement by the pin 21. The upper end of the rod 23 is provided with a nut or head 25, and disposed between the head 25 and the supporting head 24 is a coiled compression spring 26. When this rod 23 is pulled downward, the spring will be compressed. If strain on the hanger or rod 23 is relieved, 105 110

the spring will raise the rod. The lower end of this hanger rod 23 is provided with a head 27, which is screw-threaded for engagement with an I-bolt or like member 28, which forms a means whereby this hanger 23 may be drawn downward.

Coacting with the lower end of the reamer body 10 are a plurality of cutters or bits, each designated generally 29. I have illustrated three of these cutters, but it will be understood that more cutters might be used. These cutters toward their lower ends are segmental in cross section, as illustrated in Fig. 2, so that when the cutters are disposed with their upper ends within the bore of the body 10, the cutters will have their edges in approximate contact and will together form a complete circle or substantially a complete circle. Each cutter at its lower end is downwardly and outwardly beveled as at 30, and the outer surface at the lower end of the cutter is outwardly flared, as at 31, so as to form a cutting edge. Each cutter is formed with an arcuate groove 32 extending downward from the upper end of the cutter and adapted to receive the lower portion of the wall of the body 10. That portion 33 of the cutter exterior to the groove 32 at its upper edge is downwardly and outwardly beveled, as at 34, to fit the outwardly and downwardly extending lip formed by the inclined shoulder 12 so that when the cutter is raised, the lower end wall of the groove 32 bears against the lower end of the body 10 and the inclined surface 34 bears against the inclined surface 12, and thus the cutter is interlocked with the body. The upper end of the portion 33 of each cutter is outwardly and downwardly beveled outward of the bevel 34, as at 36. That portion of the cutter lying inward of the groove 32 extends above the portion 33 of the cutter and the shank 37 so formed is cut away, as at 38, on each side so as to form notches or recesses and above these notches 38, a shoulder 39 is formed, and then the shank extends straight upward and then upward and inward, as at 40.

Mounted upon the hanger 23 and normally resting upon the head 27 when the reamer is in action, is a hanger block 41 having a central, annular hub, and a disk-like portion radially slotted, at a plurality of points, as at 42, each of these slots 42 having parallel side walls and being of sufficient width to receive that portion 38a of the shank of the cutter between the notches 38, the disk 43 on each side of the slot 42 entering the notches or recesses 38 in a manner which will be obvious from Fig. 4. Thus, the several cutters are suspended from the hanger block 41 and while they have certain freedom of movement radially inward and outward, they will move vertically with the hanger rod 24 and with the hanger block 41.

Of course, the inner face of each cutter is formed with a longitudinally extending concave channel 44 to accommodate the hub of the hanger block 41.

In the actual use of this invention, by removing the pin 21 it is possible to withdraw the hanger rod 23 entirely from within the reamer body 10. The several cutters may then be engaged with the hanger block 41 in the manner described and the parts inserted within the reamer body. Then an instrument of any desired kind is thrust through the slot 22 and engages beneath the head 24, and this head is raised upward until this head 24 may be engaged by the pin 21 and firmly held in place. Under these circumstances, a downward movement of the cutters and the hanger 23 will cause a compression of the spring 26 and upon a release, the spring will act to retract the hanger and the cutters. The reamer is now ready for use and previous to inserting it in a well casing, the I-bolt 28 which may be attached to a short length of wire, a hook, or other device is pulled downward so as to carry the cutters downward until the upper ends of the portions 33 of the cutters are below the lower end of the body 10. Under these circumstances, the lower ends of the cutters may be forced inward so that the cutters will be entirely within the cylinder defined by the exterior of the reamer. A split ring 45 is then placed around the cutters so as to hold them contracted. The reamer is now inserted within the upper end of the well casing, which is of a size just sufficient to fit the enlarged portion 11, and then the reamer is lowered into the casing. When the upper end of the well casing strikes the ring 45, it shifts upward until eventually the ring is disposed above the shoulder 13, but the well casing, of course, prevents the expansion of the cutters. The reamer is further lowered into the well until the cutters pass the lower end of the well casing and as soon as this occurs, the spring 26 will draw upward on the hanger 23 and this will draw the cutters upward so that the upper ends of the portions 33 will engage within the overhanging lip 12, as illustrated in Fig. 1, thus locking the cutters securely in place and holding them very rigidly to their work. It will be noted that the tapering surface 14 permits the cutters to move upward or downward relative to the body 10 without sticking.

It will be seen that the cutters being segmental in form and extending together through nearly a complete circle offer a sufficient cutting surface after the cutters or bits have been expanded to avoid any danger of leaving lumps or rough places on the wall of the well bore. The peculiar construction of the upper part of the cutters or bits performs two or three functions. The

upper end of the portion 33 of each bit extends in beneath the downwardly extending or overhanging lip of the body 10 and gives the bit strength while it is operating.

- 5 The portion 36 projecting out beyond the circumference of the body, strikes against the casing of the well when the reamer is drawn upward, which thus acts to force the bits downward relative to the body of the 10 reamer so the bits may fold inward and come out of the hole automatically. When the bits are drawn downward and contracted, the upper portion of the outside of the bits is larger in diameter than the contracted 15 lower ends of the bits so that part of the cutter rides against the well casing, holding the edges away from the surface of the well casing and preventing them from catching in the joints of the pipe. When the bits 20 are drawn downward so that the top ends of the bits above the hanger block 41 come out of the bore 16 of the body, the upper ends of the bits may rock within the large portion 15 of the bore, allowing the lower 25 ends of the bits to move inward to thus enter the well casing, the upper ends of the bits resting against the shoulder 18, thus releasing the spring tension so that the bits will not press against the interior of the 30 well casing too hard. As soon as the bits pass beyond the lower edge of the well casing, the spring forces the upper ends of the bits to pass upwardly into the relatively smaller bore 16, thereby rocking the bits 35 on the hanger block 41 and the fulcrum and expanding the bits so that they will move upward and over the outside of the tapered face 14 of the body 10. Preferably, though not necessarily, a loose ferrule 46 is disposed 40 between the hanger block 41 and the head 24 so as to hold the head 24 up above the cutters at all times to keep the tension on the spring.

It will be noted that the several bits or 45 cutters are carried by the hanger block 41 which is so constructed that it will rotate upon the hanger rod 23. Thus the bits are swivelly connected to the body and can turn around on the body and be in operative position 50 at any time and thus avoid any accidental twisting or breakage of the bits while the tool is turned back and forth in the hole when operating.

It is also to be noted that bottom of the 55 body 10, fitting as it does into the grooves 32 of the cutters when the cutters are in use, holds the cutters in expanded position and braces the cutters firmly against any inward pressure.

60 I claim:—

1. A reamer comprising a hollow body open at its lower end, a longitudinally movable hanger rod mounted within the body and having a head at this end, the head being formed with radially extending re-

cesses, a spring urging the hanger rod upward, and a plurality of bits each having a shank extending up into the hollow body and insertible into a corresponding recess, the shanks having laterally projecting portions having rocking engagement with the head and being freely shiftable out of engagement with the head when the hanger rod is depressed to carry the shanks out of the hollow body. 75

2. A reamer comprising a hollow body open at its lower end, a longitudinally movable hanger rod mounted within the hollow body and having a head at its lower end, the head having radially disposed recesses, 80 a plurality of bits having shanks extending up into the hollow body, each of said shanks being formed to engage in a corresponding recess in the head and having outwardly extending portions above and below the 85 head and having rocking engagement therewith when the shanks are disposed within the head.

3. A reamer comprising a hollow body open at its lower end, a longitudinally movable hanger rod mounted within the hollow body, a spring urging the hanger rod upward, and a plurality of bits having shanks extending up into the hollow body and operatively engaged by said hanger rod, each 90 of said bits having rocking engagement with the hanger rod for radial movement, and each bit being formed with a recess to receive the lower end of the hollow body, the body being provided with an annular, 100 overhanging exterior lip to engage partially over the upper ends of the bits exterior to said recess. 100

4. A reamer comprising a hollow body open at its lower end, and a plurality of 105 spring-retracted bits having shanks extending into the hollow body, the bits having portions normally extending upward upon the exterior of the body when the bits are expanded, and the body having portions extending partially over the upper ends of said upwardly extending exterior portions.

5. A reamer including a hollow body open at its lower end, a plurality of longitudinally movable bits segmental in cross section and having upwardly extending shanks, 115 the upper ends of the bits being arcuately recessed to receive the lower end of the body, the upper end face of each bit exteriorly to said recess being downwardly and outwardly beveled, and the body being formed with an annular enlargement, the lower end of which extends downward and outward to form an overhanging lip partially overlying and engaging with the upwardly beveled end face of each bit. 120

6. A reamer including a hollow body open at its lower end, a plurality of longitudinally movable bits segmental in cross section and having upwardly extending shanks, 130

the upper ends of the bits being arcuately recessed to receive the lower end of the body, the upper end face of each bit exteriorly to said recess being downwardly and outwardly beveled, and the body being formed with an annular enlargement, the lower end of which extends downward and outward to form an overhanging lip partially overlying and engaging with the upwardly beveled end face of each bit, a hanger rod disposed within the body, a spring urging the hanger rod upward, and a hanger block rotatably mounted upon the rod and having rocking engagement with the shanks of the bits.

7. A reamer comprising a body formed at one end with a relatively enlarged bore and a relatively smaller bore extending therefrom, a spring supported within the hollow body at its upper end, a longitudinally movable hanger rod supported by the spring and having a head at its lower end, a hanger block rotatably mounted upon the head at its lower end and having radial notches, and a plurality of bits, segmental in cross section, and each formed with an arcuate recess at its upper end adapted to receive the lower end of the body, that portion of the bit inward of the recess being upwardly extended to form a shank and formed at its upper end to engage in the notches of the hanger block, the body being formed exteriorly with a diametrically enlarged portion undercut at its lower end, and the upper end of each bit being upwardly and inwardly beveled to engage beneath said undercut portion but project beyond it.

hanger block and engage with the hanger block.

8. A reamer comprising a body formed at one end with a relatively enlarged bore and a relatively smaller bore extending therefrom, a spring supported within the hollow body at its upper end, a longitudinally movable hanger rod supported by the spring and having a head at its lower end, a hanger block rotatably mounted upon the head at its lower end and having radial notches, and a plurality of bits, segmental in cross section, and each formed with an arcuate recess at its upper end adapted to receive the lower end of the body, that portion of the bit inward of the recess being upwardly extended to form a shank and formed at its upper end to engage in the notches of the hanger block, and engage with the hanger block, the body being formed exteriorly with a diametrically enlarged portion undercut at its lower end, and the upper end of each bit being upwardly and inwardly beveled to engage beneath said undercut portion but project beyond it.

In testimony whereof I hereunto affix my signature in the presence of two witnesses.
